UNITED STATES PATENT OFFICE.

THOMAS J. McNULTY, OF BROOKHAVEN, MISSISSIPPI.

MACHINE FOR STRIPPING OIL CAKES.

Application filed February 6, 1924. Serial No. 691,021.

To all whom it may concern:

Be it known that I, THOMAS J. McNULTY, a citizen of the United States, residing at Brookhaven, in the county of Lincoln and 5 State of Mississippi, have invented certain new and useful Improvements in a Machine for Stripping Oil Cakes, of which the following is a specification.

This invention relates to a machine for 10 removing the cloth from cotton or linseed cakes after the oil has been pressed therefrom.

An object of the invention is to provide a machine to strip the cloth from the cake in 15 an expeditious manner, without damaging the cloth or cake, or involving any danger of injury to the operator.

Another object of the invention is the provision of a machine, that is automatic in 20 operation, which upon receiving a wrapped cake will engage the cloth and automatically strip the same from the cake, upon the operation of a single lever.

It is also an object of the invention to 25 provide a cake-stripping machine of the kind indicated, which is substantial in construction, which can be manufactured economically, and which will be thoroughly efficient and practical in use.

30 With the foregoing and other objects in view, which will be apparent as the description proceeds, the invention resides in the construction and arrangement of parts, as hereinafter described and claimed, it being 35 understood that changes can be made within the scope of what is claimed, without departing from the spirit of the invention.

The invention is illustrated in the accompanying drawings, wherein:

40 Figure 1 is a front view of my improved stripper,

Figure 2 is a central longitudinal section through the same,

Figure 3 is a top plan thereof,

45 Figure 4 is a section on line 4—4 of Figure 3,

Figure 5 is a fragmentary front view showing the cloth being stripped from the cake,

50 Figure 6 is a section taken on line 6—6 of Figure 5 showing the stripper removing the cloth, and

55 Figure 7 is a fragmentary longitudinal section of a modified form showing a pair of fingers for engaging the cloth.

In carrying out the invention there is

provided a pair of supporting structures 10 and 11 made from angle iron, said structures having legs 12 and 13 and a top connecting portion 14. The supporting structures 10 and 11 have their legs 12 and 13 connected together at their lower ends by cross angle members 15, to prevent said legs from spreading. The structures 10 and 11 are connected together so as to hold the same in spaced relation by a pair of angle bars 16 and 17 secured to the legs 12 and 13 of each supporting structure.

The forward ends of the angle bars 16 and 17 extend forward of the supporting structure 10 and support a platform or table 18 intermediate its end, said table or platform having a flange 19 upon its rear side, and supported at its opposite end by brace members 20 and 21 connected at their lower ends to the lower portions of the legs 12 and 13 of the supporting structure 10.

The table or platform 18 is adapted to receive the cake thereon to be stripped and has an opening 22 therein at its central portion between the angle bars 16 and 17 for allowing a roller 23 to pass through to raise the cake. The roller 23 is reduced in diameter at its central portion so that the same will only engage the cake at its opposite ends. The terminals 24 of the roller 23 pass through slots 25 and 26 provided in the uprights 27 and 28 of a U-shaped roller supporting frame 29. Positioned upon the terminals 24 between the uprights and the roller are bearings 30 and 31 which receive the terminals 24 to support the roller. Depending downwardly from the bearings 30 and 31, are arms 32 having coiled springs 33 thereabout. Said arms 32 extend through openings in the U-shaped frame 29 and have pins 34 through their lower ends to limit the upward movement of the roller 23. The springs 33 engage the bearings 30 and 31 and the U-shaped frame 29 and yieldably hold the roller 23 in a raised position.

To guide the U-shaped frame 29 carrying the roller 23 in its upward and downward movement, I have provided braces 35 and 36 having their ends secured to the under surface of the platform or table 18, and their intermediate portion provided with recesses 37 for receiving the uprights 27 and 28 of the U-shaped frame.

For raising the U-shaped frame 29 a stud 38 is connected thereto having a pivotal connection 39 with a lever 40, which in turn

has its opposite end connected by means of a pin 41 to one end of a pivoted bell crank lever 42, said bell crank lever 42 pivoted between a pair of supporting arms 43 connected to a cross bar 44 extending from the legs 12 and 13 of the supporting structure 10. The arm 45 of the bell crank 42 has a plate 46 arranged thereon and is held in place by its ends being bent inwardly and 10 secured to said arm 45. A pin 47 extends through the arm 45 and plate 46 for engagement in a notch 48 provided in and adjacent one end of a shaft 49. The opposite end of the shaft 49 is pivotally connected 15 to a bracket 50 rigidly carried by a slidable shaft 51. Said shaft 51 is adapted to be moved by a bell crank 52 having one of its arms 53 connected thereto, the bent portion pivoted at 54 between the supports 55 attached 20 to the floor, and a foot-engaging portion 56 provided on the arm 57 on said bell crank.

A bracket 58 is secured to the under surface of the table 18 and has one end of the 25 rod 59 adjustably connected thereto as at 60, while the opposite end of the rod is connected to the arm 57 having the foot pedal 56 thereon, by a coil spring 61, said coil spring being adapted to return the foot 30 pedal when the same is released.

Attached to the arm 53 of the bell-crank 52 is pivotally and adjustably connected a cylinder 62 which receives a piston 63 that is pivotally connected to a bracket 64 attached to the angle iron 15 between the legs 12 and 13 of the support 11. The cylinder 62 has a small opening 65 therein for allowing the exit of the air contained in the cylinder in a slow manner to absorb the shock 40 when the operator releases the foot pedal 56.

A shock-absorbing means 66 is also provided for preventing the abrupt or quick descent of the U-shaped frame 29 carrying the roller 23, said shock-absorbing means 45 consisting of a rod 67 having one end thereof adjustably connected to the U-shaped frame 29 and its opposite or lower end secured to a cylinder 68, which receives a piston 69 supported by an upright bracket 70 50 secured to the floor. A small opening 71 is arranged in the cylinder 68 for the same purpose as the opening 65 in the cylinder 62.

Attached to the rod 67 is a block 72 which carries a roller 73 adapted to be engaged in 55 a notch 74 provided in the lever 75, said lever 75 having its upper end pivoted to a bracket 76 secured to the under surface of the table 18. A spring 77 is connected to the lever 75 and the cross bar 78 which extends 60 between the legs 12 and 13 of the supporting structure 10 for holding the lever 75 against the roller 73 so that the roller will engage in the notch 74 when the U-shaped frame 29 and the roller 23 are raised to hold 65 the same in such a position.

A roller 79 is also secured to the rod 67 and is adapted to engage the forward end of the shaft 49 to disengage the notch 48 from the pin 47 to prevent further upward movement of the U-shaped frame carrying the 70 roller.

A rotatable sleeve 80 is mounted in bearings 81 and 82 carried by the top or connecting portion 14 of the supporting structures 10 and 11 respectively. To prevent 75 forward sliding movement of the sleeve 80 in the bearings, a collar 83 is secured to the sleeve by a screw 84 and to prevent the sleeve against rearward sliding movement, the hub 85 is secured to said sleeve, said hub 80 85 having an annular flanged portion 86 which will hereinafter be more fully described.

The forward end of the sleeve 80 is adapted to form a roller upon which the cloth 85 from the cake is wound. A guide flange 87 is secured to the sleeve at this point to form a stop for the cake when placed upon the table 18. The flange 87 is annular and has a hub portion 88 where the same is secured 90 to the sleeve as at 89.

The sleeve 80 and the interior of the hub 88 have aligning slots 90 and 91 respectively, which receive a right-angular bent cloth engaging finger 92, said finger 92 having a portion 93 provided with a point 94 beveled to form a sharp edge at its lower surface. Said finger is adapted to be moved longitudinally with respect to the sleeve for engaging between the cloth and cake. The 100 upright portion 95 of the finger 92 is received in a slot 96 provided in the block 97 and is held therein by means of a bolt 98. A strip 99 is secured as at 100 to the interior of the sleeve 80 to be received in a groove 105 formed in the block 97 to permit sliding movement of the block with relation to the sleeve.

Attached to the rear of the block 97 is a bar 101, which is hexagonal in cross section and extends through a bearing 102 provided in the rear end of the sleeve 80. The rear end of the bar 101 is threaded at 103 to permit the attachment and assembly of a pair of flanged members 104, which when assembled provide an annular groove 105 for receiving the collar 106. Secured to the collar 106 are a pair of connecting members 107 having their outer ends attached to the lever 108 as at 109. Said lever in turn 110 is pivoted to a supporting arm 110 secured to the supporting structure 11 and has its opposite end connected to a short connecting link 111. The opposite end of the connecting link 111 connects with the upper 115 end of the lever 112 which is pivoted as at 113 to the arm 114 extending from the supporting structure 11. At the lower end of the lever 112 is provided a pin 115 to be received in a slot 116 provided in the rear end 120 125 130

of the slidable shaft 51. By the provision of the slots 116 it can be seen that the roller 23 will be elevated before the cloth-engaging finger 92 is actuated. A spring 117 is 5 connected to the lever 108 and the supporting structure 11 to yieldably hold the cloth-engaging finger 92 in its rearward position.

In order to provide for the rotation of the sleeve 80 an angular clutch flange 118 having 10 a hub 119 is secured to the sleeve 80 as at 120. Attached to the forward face of the flange 118 as at 121 is a circular friction member 122 adapted to be engaged by an annular flange 123 carried by the slidable belt pulley 124. A sleeve 125 of any desirable bearing material is arranged between the belt pulley 124 and the sleeve 80 and is adapted to be held in place by a ring member 126 secured as at 127 to the forward end 15 of the hub of the belt pulley. This ring 126 also provides one wall of an annular groove 128 formed on the hub, which receives a collar 129 to which the upper end of the lever 130 is pivoted.

20 The lever 130 is pivoted as at 131 to a supporting arm 132 secured to the top connection portion 14 of the forward supporting structure 10 and has a coil spring 133 connected to the same and to the cross bar 78. The lower end of the lever 130 has a pivoted block 134 secured thereto which has an opening therein that receives the rod 135. Adjustably positioned on the rod 135 are a pair 25 of stop collars 136 and 137, one positioned on each side of block 134, and springs 138 and 139 are positioned between each collar 136 and 137 and the block 134, to permit a yieldable stop for engaging the block when the lever 112 is swung to engage the 30 clutch faces 122 and 123.

The annular flange 86 on the hub 85 which has been referred to before, is secured to the sleeve 80 as at 140, and has an opening 142 therein that receives the bolt 143 carrying 45 the roller 144. The roller 144 is adapted to engage the upper end of the lever 145 when the same is in the position indicated in Figure 2 of the drawings, to form a stop for the rotatable sleeve 80, so that the cloth engaging finger 92 thereon will always be stopped with the cloth-engaging finger on the under surface thereof.

The lever 145 has a loose pivotal connection as at 146 to the supporting arm 147 so 50 that the block 148 on the lower end of the same that receives the rod 149 when engaged by either of the springs 150 or 151 carried by the rod 149 on the opposite sides of the block 148 and held in position by the adjustable collars 152 and 153, will swing the upper end of the lever 145 out or in the path of the rotatable roller 144. The rod 149 is connected to the upper portion of the pivoted lever 112 for sliding movement.

60 Mounted upon the angle irons 16 and 17

are a pair of brackets, 154 upon the upper side of the iron 16, and 155 on the lower member of the iron 17. A rod 156 extends through an opening 157 in the lever 145 from said brackets and held in position by 70 nuts 158 on the opposite end of said rod 156. Coil springs 159 and 160 are provided on the rod 156, one on each side of the lever 145 so that when the roller 144 strikes the lever 145, one of the springs 159 or 160 will stop the 75 rotation of the sleeve 80.

Should it be found necessary to rotate the sleeve in the opposite direction the belt that drives the belt pulley secured upon the sleeve 80 may be twisted as is often done, and the bolt 143 removed from the opening 142 and placed in the opening 161 as shown in Figure 4 of the drawing. By changing the position of the roller 144 the cloth-engaging finger 92 upon the sleeve 80 will be stopped at the desired position, when rotating the sleeve in the opposite direction.

Secured to the top or connecting section 14 of the supporting structure 10 on each side of the bearing 81 are a pair of up-standing 90 supporting members 162 and 163, which have rods 164 attached to their upper ends and extending forward for supporting rollers 165 and 166, the forward ends of the rods 164 being connected together by a bar link 167. 95 The rollers 165 and 166 are provided for a safety device to prevent the operator from coming into contact with sleeve 80 should he lose his balance while operating the machine. The rollers can also be used when a 100 cake breaks to strip half cakes.

In operation of my improved stripper, the cake having the usual cloth thereabout is placed on the table or platform 18 with the overlap of the cloth beneath the sleeve 80. 105 Downward pressure is then applied upon the foot lever 56, which will move the shaft 51 forward thus swinging the bell crank 42 upon its pivot until the notch 48 in the shaft 49 which is attached to the shaft 51 engages the pin 47 of said bell crank. The upper movement of the bell crank 42 will raise the U-shaped frame 28 carrying the roller 23, due to the connecting link 40 being attached to each. The elevating of the roller 23 will 110 raise the cake upward and against the sleeve 80 and yieldably hold the same in such position by means of the spring connection of said roller with the U-shaped frame.

Upon the upward movement of the frame 29 the rod 67 will also be raised until the roller 73 carried thereby engages in the notch 74 in the spring-held lever 75, said notch and roller will hold the roller 23 in raised position. When the roller or lug 75 also 115 carried by the rod 67 strikes the forward end of the shaft 49 the notch 38 therein will be disengaged from the pin 47 of the bell crank 42 thus preventing further upward movement of the roller 23, the shaft 49 hav- 120 125 130

ing been moved in the path of the roller or lug 79 due to its forward movement with the shaft 51.

While the above movement of parts has been taking place the lever 112 has remained in the same position due to the slot connections 15 and 16 with the rear end of the shaft 51. When the pin 15 reaches the end of the slot 16 the lever 112 will be swung upon its pivot thus causing the cloth-engaging finger 92 to be moved forward and pass partially between the cake and the cloth, the movement of said finger 92 being due to the block 97 carried upon the forward end of the 15 the slidable shaft 101, which in turn is moved by the lever 108 connected to the lever 112 through the link 111.

As the lever 112 is swung further upon its pivot the upper end of the lever 145 will be moved out of the path of the roller 144 carried by the member 86, due to the spring 150 engaging the lower end of the lever 145, said spring being connected to the shaft 149 which is attached to the lever 112. At approximately the same time a lug 169 carried by the forward end of the lever 51 will engage the pivoted spring-held lever 75 disengaging the notch 74 therein with the roller or lug 73 carried by the rod 67, thus allowing the roller 23 to descend due to its weight, said downward movement being gradual due to the slow escape of air through the opening 69 in the cylinder 68.

As the roller 23 is lowered the lever 130 connected to the lever 112 through the rod 135 and the yieldable stops 138 and 139, will be swung upon its pivot, thus sliding the belt pulley 124 until the clutch faces 122 and 123 engage each other, which will cause the sleeve 80 to rotate due to the movement of said belt pulley. The sleeve 80 will wind the cloth thereon stripping it from the cake due to the cloth engaging finger 92 holding the cloth to the sleeve.

When the cloth is entirely stripped from the cake the foot pedal 56 is released. The same will gradually move back to its first position, due to the cylinder 62 and piston 63. The upper end of the lever 145 will move in the path of the rotating roller 144, which is still revolving due to momentum, and stop the rotation of the sleeve 80 in a yieldable manner, due to the springs 159 and 160 thus preventing an abrupt stop.

Should it be desired, air or a liquid fluid may be forced into the cylinders 62 and 68 to form a hydraulic operating means for operating the machine instead of using the foot pedal 56.

In Figure 7 of the drawings I have shown a modified form of my invention, where the sleeve is greater in length and an additional cloth engaging finger 170 is provided to engage the opposite side of the cloth from that engaged by the finger 92. Said finger 170

is operated in the opposite direction to the finger 92 by a slidable rod 171 received in a longitudinal bore 172 formed in the rod 102, and slidable through said rod 102 by means of a lever 173 attached to the rear end of the same. The forward end of the rod 171 is attached to the block 174, which is keyed to the strip 99, which extends forwardly as at 175. The block 174 has a slot 176 therein which receives the upturned end 177 of the finger 170 and is held in place by the screw 178. Said finger 170 is adapted to slide through a slot formed longitudinally in the sleeve 80.

Having thus described my invention, what I claim as new is:

1. In a cake-stripping machine, a rotatable member, means for holding a cloth-wrapped cake adjacent said rotatable member, and means upon said rotatable member arranged for sliding movement with relation thereto to engage under one side of the cloth wrapper upon the cake for stripping the cloth from the cake upon rotation of said rotatable member. 90

2. In a cake-stripping machine, a rotatable member, means for holding a cloth-wrapped cake adjacent said rotatable member, and a finger carried upon said rotatable member arranged for sliding movement with relation thereto to partially engage under the cloth-wrapper upon the cake from one side thereof to hold the wrapper to said rotatable member for stripping same from said rotatable member upon rotation thereof. 100

3. In a cake-stripping machine, a rotatable member, a roller arranged underneath said rotatable member for receiving and holding a cloth-wrapped cake against said rotatable member, a finger arranged upon said rotatable member for sliding movement with relation thereto, and means for sliding said finger under one side of the cloth wrapper upon said cake for stripping the cloth therefrom upon rotation of said rotatable member. 105

4. In a cake-stripping machine, a rotatable member, a roller arranged beneath the rotatable member for receiving a cloth-wrapped cake to elevate and hold the same against said rotatable member, a finger upon said rotatable member arranged for sliding movement with relation thereto, means for sliding said finger to engage under the cloth upon the cake while the same is held against said rotatable member, and means for rotating said rotatable member after said finger has engaged under the cloth on the cake. 115

5. In a cake-stripping machine, a rotatable member, a roller arranged beneath the rotatable member for receiving a cloth-wrapped cake to elevate and hold the same against said rotatable member, a finger upon said rotatable member arranged for sliding movement with relation thereto, means for 125

sliding said finger to engage under the cloth upon the cake while the same is held against said rotatable member, and means for rotating said rotatable member after said finger has engaged under the cloth on the cake, and means for lowering said roller before the rotation of said rotatable member.

6. In a cake-stripping machine, a rotatable member, a roller arranged beneath the rotatable member for receiving a cloth-wrapped cake to elevate and hold the same against said rotatable member, a finger upon said rotatable member arranged for sliding movement with relation thereto, means for sliding said finger to engage under the cloth upon the cake while the same is held against said rotatable member, and means for rotating said rotatable member after said finger has engaged under the cloth on the cake, and means to stop the rotation of said rotatable member so that said finger thereon will be in a position to engage under the wrapper of the next cake.

15 7. In a cake-stripping machine, a rotatable member, a roller arranged beneath said rotatable member for receiving a cloth-wrapped cake thereon, a frame for yieldably supporting said roller therein, means for elevating said frame to yieldably hold the cake between said roller and said rotatable member, and a finger upon said rotatable member for engaging the cloth upon the cake to strip the same therefrom upon rotation of said rotatable member.

20 8. In a cake-stripping machine, a rotatable member, a roller arranged beneath said rotatable member for receiving a cloth-wrapped cake thereon, a frame for yieldably supporting said roller therein, means for elevating said frame to yieldably hold the cake between said roller and said rotatable member, and a finger upon said rotatable member for engaging the cloth upon the cake to strip the same therefrom upon rotation of said rotatable member.

25 9. In a cake-stripping machine, a rotatable member, means for elevating and holding a cake against said rotatable member, a finger upon said rotatable member arranged for movement with relation thereto to engage the cloth upon the cake, and means arranged to automatically elevate said holding means, to engage said finger to the cloth, lower the elevating and holding means, and then rotate said rotatable member to strip the cloth from the cake, upon operation of a single member.

30 10. In a cake-stripping machine, a rotatable member, means for elevating and holding a cake against said rotatable member, a finger upon said rotatable member arranged for movement with relation thereto to engage the cloth upon the cake, and means arranged to automatically elevate said holding means, to engage said finger to the cloth, to lower the elevating and holding means, and then rotate said rotatable member to strip the cloth from the cake upon operation of a single member, and means to stop rotation of said rotatable member so that said finger will be in proper position to engage the cloth of the next cake upon release of said operating member.

35 11. In a cake-stripping machine, a rotatable member, a roller arranged beneath said

rotatable member for receiving a cloth-wrapped cake thereon, a frame for yieldably supporting said roller therein, means for elevating said frame to yieldably hold the cake between said roller and said rotatable member, and a finger upon said rotatable member for engaging the cloth upon the cake to strip the same therefrom upon rotation of said rotatable member, and means for preventing shocks when the roller is returned to its lower position.

12. In a cake-stripping machine, a rotatable member, a roller positioned beneath said rotatable member adapted to receive a cloth-wrapped cake to elevate and hold the same against said rotatable member, an annular flange upon said rotatable member adapted to rotate therewith to act as a stop when placing the cake upon the said roller, and a finger upon said rotatable member for engaging the cloth of said cake to strip the same from the cake upon rotation of the rotatable member.

13. In a cake-stripping machine, a rotatable sleeve having a slot in the side wall thereof, means beneath said sleeve for receiving, elevating and holding a cloth-wrapped cake against said sleeve, a block within said sleeve arranged for sliding movement therein, a finger extending through the slot in said sleeve and held by said block, and means for sliding said block in said sleeve to engage said finger with the cloth upon the cake to separate the same from the cake upon the rotation of the sleeve.

14. In a cake-stripping machine, a rotatable sleeve, having a slot in the side wall thereof, means beneath said sleeve for receiving, elevating and holding a cloth-wrapped cake against said sleeve, a block within said sleeve arranged for sliding movement therein, a finger extending through the slot in said sleeve and adjustably held by said block, a shaft attached to said block and extending through one end of said sleeve, and means attached to the end of said shaft extending to said sleeve to slide said finger between the cloth and the cake so that the same will be separated upon rotation of the sleeve.

15. In a cake-stripping machine, a rotatable member, means beneath said rotatable member for receiving, elevating, and holding a cloth-wrapped cake against said rotatable member, and means upon said rotatable member arranged for sliding movement in relation thereto to engage between the cloth upon the cake on both sides thereof to strip the cloth from the cake upon rotation of said rotatable member.

16. In a cake-stripping machine, a rotatable member, means beneath said rotatable member for holding a cloth-wrapped cake against said rotatable member, a pair of

fingers carried by said rotatable member and arranged for sliding movement with relation thereto, and means for sliding said fingers to engage the opposite sides of said cake under the cloth to strip the same from the cake upon rotation of said rotatable member.

In testimony whereof, I have affixed my signature in the presence of two witnesses.

THOMAS J. McNULTY.
